WIRE HOLDING AND PRESTRESSING DEVICE

Oswald Mazzei, New York, N. Y., assignor to Aircraft Hardware Mfg. Co. Inc., New York, N. Y., a corporation of New York

Application July 26, 1950, Serial No. 175,925

5 Claims. (Cl. 254—67)

1

This invention relates to a new and improved wire holding and prestressing device designed to hold, draw and maintain reinforcing wire taut in concrete pouring forms during the concrete pouring and subsequent setting and hardening period and thereby produce a more rigid and sturdy concrete structure.

This improved device operates to releasably hold, prestress and maintain taut any gage wire within the concrete pouring form during the concrete pouring, setting and drying period, and thereafter may be readily and easily removed and reused in successive concrete pouring operations.

Heretofore it has been the generally accepted practice in applying reinforcing wire to concrete pouring forms, to initially thread one or both ends of the reinforcing wire so that when the wire is arranged in the pouring form, nuts may be applied thereto and used to draw the wire taut. This prior art method of tightening the reinforcing wire involves time and labor in first accurately measuring and cutting the wire into appropriate lengths, in then applying threaded end sections to each wire length, and finally in applying washers and nuts to draw the wire lengths taut.

The improved wire holding and prestressing device constructed in accordance with this invention may comprise a sturdy casing which is designed to telescope over the projecting end section of the reinforcing wire. The casing has a foot section at one end thereof designed to be removably secured to the end wall of the pouring form through which the end section of the reinforcing wire projects. The casing encloses a reciprocable block presenting a pair of spaced legs. The spaced legs have a hinged dog and a pair of spaced stud pins positioned therebetween which are operable to securely grip the end section of the reinforcing wire when threaded between the dog and the spaced stud pins. The reciprocable block has a tubular shaft section extending from one end thereof through which the reinforcing wire is threaded, the shaft section projecting through a bore in a head section provided at the other end of the casing. The shaft section is externally threaded and carries a nut designed to seat against the flat end of the head section of the casing so that when the nut is manipulated, axial movement will be imparted to the block within the casing.

The casing is also provided with a tapered cam plate secured to the interior surface thereof which cooperates with the heel of the dog to

5 thereby depress the dog and bend the reinforcing wire between the spaced stud pins and thereby form a gripping kink therein when the exterior nut is initially manipulated. When the nut is further manipulated, the block is further drawn toward the head section of the casing to thereby draw the reinforcing wire to the desired tautness.

10 By the use of this improved wire holding and prestressing device, the prior art time consuming practice of accurately measuring, cutting and subsequent threading the ends of the reinforcing wire to accommodate washers and nuts, may be entirely eliminated.

15 An object of this invention is to provide an improved wire holding and prestressing device which may be repeatedly used to hold and prestress various gages of reinforcing wire strung through concrete pouring forms, which is relatively simple in construction, inexpensive to manufacture, durable in service, and permits effective prestressing of the reinforcing wire with accompanying substantial savings in time and labor.

20 25 Other objects and advantages of this invention will become apparent as this disclosure proceeds.

30 This improved wire holding and prestressing device has certain details of construction and combination of parts as will hereinafter be described and shown in the accompanying drawing, wherein like numerals of reference represent like parts in the several views, and in which;

35 Fig. 1 is a side elevational view of a concrete pouring form through which a plurality of reinforcing wires have been strung, and which are held taut and prestressed by the application thereto of the improved wire holding and prestressing devices made in accordance with this invention.

40 Fig. 2 is an end view of the concrete pouring form shown in Fig. 1 illustrating one end wall of the concrete pouring form with the wire holding and prestressing devices applied thereto.

45 Fig. 3 is a longitudinal cross-sectional view of the wire holding and prestressing device as the same would appear when attached to an end wall of a concrete pouring form, this view showing the wire as threaded through the device and before the wire has been stretched.

50 Fig. 4 is a transverse cross-sectional view of the device as the same would appear when viewed in the direction of the arrows 4—4 of Fig. 3.

Fig. 5 is another longitudinal cross-sectional view of the wire holding and prestressing device

applied to the end wall of the pouring form and as the same would appear after the wire threaded therethrough has been prestressed.

Fig. 6 is a transverse cross-sectional view of the device as the same would appear when viewed in the direction of the arrows 6—6 of Fig. 5.

Fig. 7 is a transverse cross-sectional view of the device illustrating the position of the prestressed wire when the device has been rotated through 90° to thereby permit removal of the device from the wire.

Fig. 8 is a plan view of the wire holding block and associated wire gripping dog; and

Fig. 9 is a fragmentary elevational view of a concrete pouring form in which one end of the reinforcing wire is bent over the adjacent end wall of the form so that only one wire holding and prestressing device attached to the other end of the wire need be employed to prestress the wire.

Wire holding and prestressing devices constructed in accordance with this invention are designed for use in connection with concrete pouring forms, which as shown for purposes of illustration in Figs. 1, 2 and 8, may be said to generally comprise a pair of spaced end walls *a* connected by side walls *b*. The several lengths of reinforcing wire *w* extend lengthwise through the pouring form so as to become embedded in the concrete when the forms are filled with fluid concrete. The end sections *w'* of the wire lengths *w* project through the end walls *a* of the pouring forms and the wire holding and prestressing devices *A* of this invention are designed to be removably attached to the projecting end sections *w'* of the wire lengths and to seat against the adjacent end wall *a* of the pouring form.

This improved device for holding and prestressing concrete reinforcing wire generally comprises a casing *10* which may be made of stamped or cast metal. The casing *10* may have a circular or polygonal interior bore *11* which is open at the base end thereof and is provided with a head section *12* at the other end thereof, as shown in Figs. 3 and 5. The base end of the casing is provided with an outwardly flared foot section *13* designed to seat against the end wall *a* of the pouring form. The foot section *13* may be provided with a plurality of spaced holes *14* through which nails or like securing means *c* may be inserted to temporarily secure the casing *10* to the end wall *a* of the pouring form.

A block *15* is designed to reciprocate within the bore *11* of the casing and may be generally U-shaped in configuration, presenting a head portion *16* having a pair of spaced legs *17* extending therefrom in the direction of the base end of the casing *10*. The reciprocating block *15* has a tubular shaft section *18* extending from the head portion *16* thereof. The bore *19* in the tubular stem section *18* is of ample diameter to permit various sizes of reinforcing wire to be threaded therethrough. The shaft section *18* extends through a conforming bore *12'* in the head section *12* of the casing *10*. A sturdy manipulating nut *20* threads over the heavy external threads *21* which encircle the stem section *18*, with the base of the nut *20* designed to seat against the flat end face *22* of the head section *12* of the casing *10*.

Wire gripping means associated with the leg portions *18* of the reciprocable block *15* is provided to firmly and tenaciously grip the end section *w'* of the reinforcing wire *w* threaded between the leg portions *17* and through the bore *19* in the stem section *18*. The wire gripping

means comprises a pair of spaced stud pins *25* which are secured to the leg portions *17* and span the space therebetween, as shown in Figs. 3, 5 and 8. The stud pins *25* are so located that the end section *w'* of the reinforcing wire will initially lightly rest thereon when the wire end section is threaded through the bore *19* of the stem section *18*. A wire gripping dog *26* is positioned directly above the wire supporting studs *25* and is hingedly mounted at one end thereof between the spaced leg portions *17* of the reciprocable block *15* by a hinge pin *27* which extends between and is secured to the special leg portions *17* of the block *15*. The lower edge of the dog *26* is provided with a nose portion *28* formed integrally therewith which is located so that it may be swung between the spaced wire supporting studs *25*.

When the reciprocable block *15* is in the retracted position shown in Fig. 3, the wire gripping dog *26* is free to swing upwardly so that the straight end section *w'* of the wire can be strung between the wire supporting studs *25* and the nose portion *28* of the dog *26* with the heel portion *29* of the dog adjacent the interior surface of the casing bore *11*. However, means are provided to forcibly swing the dog *26* downwardly so that the nose portion *28* will project between the wire supporting studs *25* to thereby form a kink *w''* in the wire and thus ensure a firm grip on the wire when the reciprocable block *15* is drawn towards the head section *12* of the casing. The means for manipulating the dog *26* into gripping engagement with the wire comprises a cam plate *30* which may be secured as by screws *31* to the inner surface of the casing *10* directly above the pivotally mounted dog *26*. The cam plate *30* has a tapered camming surface *32* against which the heel portion *29* of the gripping dog may cam when the reciprocable block *15* is drawn toward the head section *12* of the casing *10*.

By an appropriate rotation of the manipulating nut *20*, the reciprocable block *15* may be drawn toward the head section *12* of the casing to thereby drag the heel portion *29* of the gripping dog *26* longitudinally along the tapered camming surface *32* of the cam plate *30* in a manner to forcibly drive the nose portion *28* thereof against that portion of the reinforcing wire which spans the wire supporting stud *25*, to thereby form a decided bend or kink in the stud spanning portion *w''* of the wire, as illustrated in Fig. 5. Continued tightening manipulation of the nut *20* serves to draw the reinforcing wire taut and maintain the reinforcing wire in the desired taut and prestressed condition during pouring of the concrete into the pouring form and hardening thereof to the desired hardness.

To ensure smooth reciprocating movement of the block *15* within the casing *10*, a guide plate *35* is provided which is positioned between the leg portions *17* of the block *15* and is secured as by screws *36* to the adjacent inside face of the casing *10*. The side edges *37* of the guide plate *35* have bearing contact with the inside faces of the leg portions *17* of the block *15* and thus prevent rotative movement of the block *15* within the casing *10* and ensure smooth reciprocating movement thereof. The guide plate *35* additionally serves as a stop means to limit the retracted movement of the block *15*. It will be noted that when the reciprocable block *15* is in its fully retracted position as indicated in Fig. 3, the inside face of the head portion *16* of the block *15* will abut against the end *38* of the guide plate *35* to thereby also limit the retracted posi-

tion of the block 15. The guide plate 35 as well as the leg portions 17 of the block 15 are of sufficient length so that the side edges 37 of the guide plate 35 are in constant guiding contact with the leg portions 17 when the block has been advanced to its maximum wire tightening position.

This improved device can be easily and quickly detached from the end section, w' of the reinforcing wire and removed from the end wall a of the pouring form by first loosening the manipulating nut 20; then withdrawing the nails c from the foot section 13 of the casing 10, and thereupon rotating the casing 10 through an angle of approximately 90° as shown in Fig. 7. Rotation of the casing 10 through an angle of 90° operates to likewise rotate the gripping dog 26 and wire supporting studs 25 through a corresponding angle, so that the nose portion 28 of the dog 26 will swing out of the kink depression w'' in the wire and lie against one of the relatively straight side faces thereof, and with the wire supporting studs 25 positioned adjacent the other relatively straight side face of the wire. With the gripping dog 26 and wire supporting studs 25 thus located, the entire casing 10 and its associated reciprocable block 15 can be drawn off from the projecting end section w' of the reinforcing wire w .

This improved wire holding and prestressing device may be sturdily constructed from a relatively few and simple parts at relatively low cost, and can easily and quickly be attached and detached to various sizes of concrete reinforcing wire. These improved devices provide a convenient and practical accessory to mechanics engaged in building concrete structures which can be used to effect substantial savings in time and labor in holding, prestressing and maintaining taut the reinforcing wires in concrete forms.

While certain novel features of this invention have been disclosed hereto, and are pointed out in the claims, it will be understood that various omissions, substitutions, and changes may be made by those skilled in the art without departing from the spirit of this invention.

What I claim is:

1. An improved device designed to prestress and maintain reinforcing wire taut comprising a casing, a head section at one end of said casing, wire holding means reciprocable in said casing, a shaft portion extending from said wire holding means and projecting from the head section of said casing, and take up means associated with said shaft portion coacting with said head section to manipulate said wire holding means within said casing, said wire holding means including a reciprocable block, a wire gripping dog pivotally mounted on said block, spaced studs designed to support an end section of the wire extending into said casing; and cam means within said casing operative to manipulate said dog into gripping engagement with the stud spanning portion of the wire end section.

2. An improved wire holding and prestressing device including, a casing designed to receive an end section of the wire, said casing having a foot section at one end thereof designed to seat against the wall of a concrete pouring form and a head section at the other end thereof, a block reciprocable in said casing, a shaft portion extending from said block through the head section of said casing, means associated with said shaft portion coacting with the head section of said casing for

reciprocating said block, spaced studs mounted on said block providing support for the end section of the wire threaded through said casing; a wire gripping dog pivotally mounted on said block, a cam member fixed to the interior of said casing and extending longitudinally thereof, said dog having a heel portion designed to ride over said cam member and a nose portion designed to depress the stud spanning portion of the wire end section to form a kink therein when said block is drawn towards the head section of said casing by said manipulating means.

3. An improved wire holding and prestressing device including, a casing designed to receive an end section of a wire, said casing having a foot section at one end thereof designed to seat against the wall of a concrete pouring form and a head section at the other end thereof, a block reciprocable in said casing, said block having a head portion and a pair of spaced legs extending toward the foot section of said casing, a shaft portion extending from the head portion of said block through the head section of said casing, means cooperating with said shaft portion and said head section for reciprocating said block within said casing, spaced studs extending between the legs of said block providing support for the end section of the wire threaded through said casing, a wire gripping dog pivotally mounted between said legs, and a cam plate fixed to the interior of said casing and extending longitudinally thereof, said dog having a heel portion designed to ride over said cam plate and a nose portion designed to depress the stud spanning portion of the wire end section to form a kink therein when said block is drawn towards the head section of said casing by said manipulating means.

4. An improved wire holding and prestressing device including, a casing having a foot section at one end thereof designed to seat against the wall of a concrete pouring form, a head section at the other end of said casing, a block reciprocable in said casing, an externally threaded tubular shaft portion extending from one end of said block through the head section of said casing, said casing and tubular shaft section being designed to receive an end section of a wire threaded therethrough, a manipulating nut in threaded engagement with said tubular shaft portion and designed to seat against the end face of said head section, spaced studs associated with said block providing support for the end section of the wire threaded through said casing, a wire gripping dog pivotally mounted on said block, a cam member fixed within said casing and extending longitudinally thereof, said dog having a heel portion designed to ride over said cam member and a nose portion designed to depress the stud spanning portion of the wire end section to form a kink therein when said block is drawn towards the head section of said casing by said manipulating nut.

5. An improved wire holding and prestressing device including, a casing having a foot section at one end thereof designed to seat against the wall of a concrete pouring form, a head section at the other end of said casing, a block reciprocable in said casing, said block having a head portion and a pair of spaced legs extending toward the foot section of said casing, an externally threaded tubular shaft portion extending from the head portion of said block through the head section of said casing, said casing and tubular shaft portion being designed to receive

an end section of a wire threaded therethrough, a manipulating nut in threaded engagement with said tubular shaft portion and designed to seat against the end face of said head section, spaced studs extending between the legs of said block providing support for the end section of the wire threaded through said casing, a wire gripping dog pivotally mounted between said legs, a cam plate fixed to the interior of said casing and extending longitudinally thereof, said dog having a heel portion designed to ride over said cam plate and a nose portion designed to depress the stud spanning portion of the wire end section to form a kink therein when said block is drawn towards

the head section of said casing by said manipulating nut, and means within said casing for guiding the reciprocable movement of said block.
